MULTIBLADED RAZOR

Glenn S. McCune, Richmond Heights, Mo.

Application January 26, 1945, Serial No. 574,729

4 Claims. (Cl. 30—50)

1

This invention relates to safety razors, and has for its principal object the provision of a multi-bladed razor which is simple in its construction, inexpensive to make and possessed of novel features making it possible to give a close, smooth shave with but a single pass over the skin.

A specific object of the invention is to provide a razor head and handle which are made from a single piece of material shaped, folded and united to form a unit capable of accommodating a plurality of removable blade-holding members.

It is also an object of the invention to provide a safety razor which may be assembled and disassembled with ease and rapidity.

A further purpose of the invention is to provide a safety razor having removable blade-mounting means in which extra blades may be positioned for ready placement in a razor head.

A still further object of the invention is to provide a safety razor having the qualities outlined in the foregoing objects that is neat in appearance and easy to clean and dry.

Other objects and advantages will become apparent as the description proceeds, and a more comprehensive understanding of the invention will be afforded from the following detailed description when considered in connection with the accompanying drawing in which like numerals have been used throughout the different views to designate like parts and in which:

Fig. 1 is a side elevational view of a razor embodying a form of the invention and showing the same assembled;

Fig. 2 is a rear elevational view of the razor illustrating its construction;

Fig. 3 is an ideal vertical sectional view taken along the line 3—3 of Fig. 2 showing the position of the blades and their holders and the clamping mechanism for holding them in position;

Fig. 4 is a cross-sectional view of the razor handle taken along the line 4—4 of Fig. 1;

Fig. 5 is a plan view of a removable blade-holding member which holds a blade in position in the razor head;

Fig. 6 is a perspective view of a movable skirt carried in the razor head to close the ends thereof;

Fig. 7 is an ideal sectional view illustrating an alternate method of mounting the blade-holding members in the razor head; and

Fig. 8 is a plan view of the blank from which the body of the razor is formed.

In its preferred form, the razor comprises a shaving head 11, a handle 12, and separate blade-holding members 13, 14 and 15, assembled as illustrated in Figs. 1 and 3. The head of the razor

2

is so shaped that when the blade-holding members, or separators, are clamped in their proper places, a blade 16, held on the separator 13, is positioned for shaving. This blade is presented to a given point on the skin, first. A second blade 17, and a third blade 18, held, respectively, on the separators 14 and 15, are arranged to follow the blade 16 passed this point in the order named. Thus, the three blades are disposed in tandem to be passed over the skin one after the other. Their cutting edges are substantially parallel and each blade is held firmly by a suitable clamping device which holds the separators in the head.

In the embodiment of the invention illustrated, 15 this clamping means takes the form of a screw 19 which is threaded at 21 to engage a nut 22 secured in the handle 12. The screw 19 extends through a bearing 23, which closes the end of the handle 12 to prevent the collection of dirt and 20 foreign matter in this part of the razor. A knurled knob 24, forming a head for the screw 19, extends from the end of the handle and provides a means for rotating the screw. The opposite end of the screw forms a bearing surface 25 which acts against a skirt 26 undergirding the separators 13, 14 and 15. This skirt is attached to the head at each of its sides and pivots about the pins 27 and 28 so as to be movable under the forces developed by turning the screw 19. This 25 latter action moves the skirt upwardly and clamps the separators 13, 14 and 15, together with the blades 16, 17 and 18, firmly between it and the top of head 11. Two wings 29 and 30 of the skirt 26 serve to close the open ends of the head and enhance the lines thereof.

The removable blade-mounting means employed in the head 11 may take the form of the separators shown in Fig. 5. Each separator, three of which are shown superposed, comprises a body plate 31, 31a and 31b, blade clamps and positioning projections. For each separator two blade clamps 32 and 33 are formed from cut sections of the plates 31, 31a and 31b, and are bent so as to hold a double edged blade 34 in position thereon. One end 35 of each plate extends a fixed distance from the blade clamps 32 and 33 thereof, that is a function of the dimensions of the blade used. This dimension of the separator is so chosen that when the shoulders 36 and 37 of the blade are in abutment with the clamps 32 and 33, the cutting edge of the blade will extend beyond the end 35 only an amount sufficient to give a close, comfortable shave with absolute safety.

Each of the separators is similar in shape with

the exceptions of slightly different longitudinal dimensions (Fig. 5) and the positioning projections individual to each which assure the proper placement of the blade-holding device in the head. It will be appreciated that each of the blades must occupy a position in the head which gives optimum shaving results and still provides absolute safety. These conditions are met by maintaining each of the blades at a certain angle with each other and in proper spaced relationship so that they converge on what may be termed as a shaving point. The blade angles are fixed by the position of the slots in the back of the razor head and the spacing of the blades by the length of each separator. Since it is imperative that all critical relationships of the parts be maintained, provision against the incorrect placement of the separators in the head is made.

To accomplish this purpose, a positioning projection 38 for the separator 15 is provided and is so sized as to fit in a slot 39 (Fig. 2) in the back of the head 11. Likewise, a pair of projections 41 and 42 and a larger projection 43 for the separators 16 and 13, respectively, are provided. These projections are insertable in their distinctly different slots, which are the slots 44 and 45 for the projections 41 and 42 and a slot 46 for the projection 43.

It is thought advisable at this point to call attention to the salient fact that, while it is necessary for the proper angular relationship of the blades to be maintained when a plurality of blades are used in the razor, it is not necessarily so when a single blade is used, if such use is ever occasioned. In other words, if only one separator is inserted in the head and the screw 19 is adjusted to clamp this separator in position, it is obvious that the blade carried on the particular separator will be at a somewhat different angle than it would be if three separators were inserted in the head. This condition presents no problem, however, since it would be only required to alter the angle at which the razor is applied to the skin to bring the cutting edge of the blade into proper shaving position. The same would be true if only two blades were used since the angular relationship of the blades, together with their proper spacing would be maintained by their proper placement in the head, and it would only be required to rock the entire razor into a different cutting position to bring both of the blades into proper shaving position. This, in effect, would compensate for the change in the position of the shaving point due to the absence of one separator.

The arrangement for mounting the blades in the head of a razor just described provides for quick, accurate placement of the blades and assures a convenient way for carrying extra blades. Here, the extra blades may be positioned on extra separators and they are ready for instant use. Moreover, by mounting the blades in this manner, all of the parts of the razor are readily accessible for thorough cleaning and drying. It is conceivable, however, that for some uses it may be desirable to fix the separators in the head at the expense of these distinctly unique advantages. This may be done as illustrated in Fig. 7. Instead of the projection-slot arrangement, the separators, such as 47, 48 and 49, are formed to be pivotally attached to the back of a head 11a by suitable hinges 51, 52 and 53, respectively. In all other respects the parts are like those previously described.

As contemplated in its present embodiment, the razor just described may be produced inexpensively by the following method. The body of the razor comprising the head 11 and the handle 12 is made from a single piece of material such as that shown in Fig. 8. This piece of material, which may be shaped by stamping, is also punched to form the slots 39, 44, 45 and 46, and a hole 54 provided for the screw 19. The sections 55, 56, 57, 58 and 59 form the top, the two sides, the back and the bottom, respectively, of the head 11. The tubular handle 11 is formed from the sections 61, 62 and 63 and assumes a triangular shape (Fig. 4) which makes the razor easy to hold and prevents the handle from turning in the hand. As uniting members, the wing sections 64, 65, 66, 67, 68 and 69 also serve to reinforce the head so that the proper angular relationship between the top 55 and the bottom 58 will always be maintained despite the forces applied to clamp the blade-holding members in the head.

After the blank shown in Fig. 8 has been shaped, the body of the razor is formed by bending and folding it along the section lines indicated and as illustrated in Fig. 2. Here the sections 66 and 67 are bent under the sides 56 and 57, as the top 55 is bent downwardly and the wings 64 and 65 are folded over the back section 58. The bottom section 59 is then bent upwardly as is the handle section 62 until both are at a proper angle with the top, and the wings 68 and 69 are folded under the bottom section 58. Next, the wings 64, 65, 66, and 69 are secured to the back and bottom sections 58 and 59 as by spot welding, and the assembly is completed by fixing the skirt 26, also formed by stamping, in its proper place.

The separators may be made also by stamping them to the desired shape and forming the guard 35 as a part thereof. By a subsequent operation, the blade clamps 32 and 33 are bent into shape from the sections of the plate 31 cut in the previous operation.

In operation, the razor is quickly conditioned for use by positioning the blades on the separators, and, while holding the razor so that the mouth of the head extends upwardly, dropping them into their proper places in the head. The knob 24 at the foot of the handle is then turned to clamp the separators in their proper shaving positions. During the clamping action, the weight of the separators together with their blades hold them in their slots and keep them flush with the back of the head 11.

By loosening the screw 19, the separators may be withdrawn from the head 11, their blades removed, and the parts cleaned and dried for subsequent use. Further, the razor is so shaped that it may be flushed clean with tap water while completely assembled.

While specific embodiments of the invention have been illustrated and described, it is apparent that many changes and widely different embodiments could be made thereto without departing from the invention in spirit or scope. Accordingly, the recitations and representations herein made are to be interpreted as illustrative only and not in a limiting sense, and, insofar as the changes and embodiments to which the invention is susceptible fall within the appended claims, they are included as if described.

What is claimed is:

1. In a safety razor, a shaving head having a top, bottom, back and sides, a handle attached to the bottom of said head, a plurality of blade-

mounting members having projections passed into slots provided in the back of said shaving head, said members also having means associated with each to clamp and hold a blade in position with respect to an end thereof, and a threaded member extending through said handle having one end thereof bearing against the lowermost of said mounting members and turnable to clamp all mounting members and the blades carried thereon into shaving position between the top of said head and the lowermost mounting member, whereby said blades are maintained at acute angles with each other and with their cutting edges substantially parallel.

2. In a safety razor, a shaving head having a top, bottom, back and sides, a handle attached to the bottom of said head, a plurality of blade-mounting members hinged to the back of said head, said members having means associated therewith for clamping and holding a blade in position with respect to a guard formed as a part of each of said members, and a threaded member extending through said handle having one end thereof bearing against the lowermost of said mounting members and turnable to clamp all mounting members and the blades carried thereon into shaving position between the top of said head and the lowermost mounting member, whereby said blades are maintained at acute angles with each other and with their cutting edges substantially parallel.

3. In a safety razor, a shaving head having a top, bottom, back and sides, a handle attached to the bottom of said head, a plurality of blade-mounting members having portions thereof supported on the back of said head, a skirt undergirding said mounting members and pivotally attached to the sides of said head whereby to be

movable with said members and close the ends of said head between the lower edge of its sides and its bottom; and a threaded member extending through said handle having one end thereof bearing against said skirt and turnable to clamp all mounting members and the blades carried thereon between said skirt and the top of said head whereby said blades are maintained at acute angles with each other and with their cutting edges held substantially parallel to present the same in tandem to an area to be shaved.

5 4. As an article of manufacture, a razor blade holding device comprising a single piece of material shaped, folded and joined to form a razor head and handle both integral with each other, a plurality of blade-holding members carried in said razor head having means associated with each to clamp and hold a blade in position with respect to one end of each of said members, and means operable to clamp and hold said blade-holding members in said razor head to maintain them in positions relative to each other whereby the cutting edges of blades held thereon are presented in tandem to an area to be shaved.
